FOREIGN PATENT DOCUMENTS

WO 1990012523 A1 11/1990

Primary Examiner — Janice Seeger

(57) **CLAIM**

We claim the ornamental design for a desk, as shown and described.

DESCRIPTION

FIG. 1 is a front perspective view of a desk, according to an embodiment;

FIG. 2 is a rear perspective view of a desk of FIG. 1;

FIG. 3 is a front view of a desk of FIG. 1;

FIG. 4 is a rear view of a desk of FIG. 1;

FIG. 5 is a left side view of a desk of FIG. 1;

FIG. 6 is a right side view of a desk of FIG. 1;

FIG. 7 is a top view of a desk of FIG. 1; and,

FIG. 8 is a bottom view of a desk of FIG. 1.

The dashed lines and broken lines are for purposes of illustrating environmental structure and form no part of the claimed design.
